TIME STAMP

Filed Dec. 20, 1926

FIG. I

FIG. II

FIG. III

FIG. V

FIG. IV

INVENTOR
J. W. ADLON

BY J. G. COOK
ATTORNEY

UNITED STATES PATENT OFFICE.

JOSEPH W. ADLON, OF ST. LOUIS, MISSOURI.

TIME STAMP.

Application filed December 20, 1926. Serial No. 155,904.

My invention relates to a new and useful improvement in time stamps and has for its object to provide a highly efficient and relatively inexpensive device which is economical to manufacture, easy to assemble, and requires a minimum of power from the time-keeping element to operate the movable parts.

Fig. I is a front view of my improved time stamp partly in section and partly in dotted lines.

Fig. II is a side elevation of my improved time stamp partly in section.

Fig. III is an enlarged view taken through the housing with the watch removed.

Fig. IV is an enlarged detail sectional view through the bottom portion of my improved time stamp showing the case of the time-keeping member partly broken away.

Fig. V is a bottom view of my improved time stamp.

In the drawing, A designates a time-keeping member, preferably a watch provided with stem winding and setting mechanism B. C is a handle secured by a threaded pin 25 D to a curved portion E which is secured to the housing for the time-stamping mechanism. The portion E is connected to the housing 1 by four screws 2 and 3, respectively. Holes 4 are drilled in the casing of 30 the watch A directly opposite each other, and into these holes the inner ends of the screws 3 are adapted to project for positively holding the watch A in position in the housing 1.

35 5 is a pinion upon which the minute hand of the watch A is mounted on the face side of said watch. 6 is a member securely fastened by frictional engagement to the pinion 5 so as to positively rotate therewith, and 7 is a lever carried by said member 6. 8 is a cylindrical drum having a slot 9 for the reception of the lever 7. The drum 8 is connected to the upper end of a shaft 10, said shaft being adapted to rotate with the 45 drum 8. 11 is a small toothed wheel also mounted on the shaft 10 and securely in contact with the lower face of the drum 8. 12 is a large toothed wheel meshing with the toothed wheel 11. The toothed wheel 12 has a smaller toothed wheel 13 associated therewith, both the toothed wheels 12 and 13 being mounted on a shaft 14 fixed in the housing 1.

15 15 is a large toothed wheel meshing with the small toothed wheel 13, said toothed wheel 55 15 being carried by a sleeve 16 mounted for rotation in the housing 1. It will be noted in

Fig. IV that the sleeve 16 surrounds the shaft 10. 17 is a cylindrical drum mounted on the lower end of the sleeve 16, and to this is connected a small rubber indicating pointer 18. 19 is a small cylindrical drum mounted on the lower end of the shaft 10 and this carries a rubber block 20, which is provided with an indicating pointer 21 (see Fig. V) also of rubber. 22 is a rubber impression member which is provided with a representation of a watchface bearing the numerals 1 to 12, as shown in Fig. V. 23 is a space provided in the rubber block 22 in which may be inserted the appropriate type plugs to indicate the 70 month, day and year.

In the operation of my device the watch A is open-face and of a standard size and variety, having a rear plate for the back of said watch, which plate I provide with a 75 circular opening, as shown at 24 in Fig. IV, in order that the cylindrical drum 8 may freely fit into said opening 24. I then drive the member 6 carrying the lever 7 securely upon the shaft 5 which is the end opposite 80 to that end which carries the minute hand of said watch. The watch A is then placed face up in the housing 1 and secured in position therein by the screws 3, the ends of which pass into the holes 4 which I make in the sides of the watch casing A to receive the same. The lever 6 then fits into the slot 9 in the cylindrical drum 8, and by means of said lever's connection with the shaft 5 causes 85 said cylindrical drum 8 to rotate. 90

It will be noted that the shaft 7 is of sufficient length so that minor inaccuracies may readily be taken care of and yet have sufficient operative length to at all times fit into operative relationship with the cylindrical 95 drum 8.

The small gear wheel 11 and the cylindrical drum 8 being mounted together on the shaft 10, rotation of said shaft is caused by the drum 8, which shaft in turn drives the 100 small cylindrical drum 19 which carries the hour-indicating pointer 18. The small gear wheel 11 meshes with the large gear wheel 12, which in turn is fixed to the small gear wheel 13, and these are mounted for rotation on the shaft 14 fixed in the housing 1. The large gear wheel 15 in turn meshes with the small gear wheel 13, which drives the sleeve 16, which in turn drives the cylindrical drum 17 mounted on the lower end of said sleeve 110 16, which drum carries the minute-indicating pointer 21. The drum 16 and the drum 17

rotate freely within the rubber member 22. The indicating figures on the rubber member 22 show the hours and minutes and the pointers 18 and 21 indicate just what hour 5 and substantially what minute the watch A records. When the month, day and year plugs are inserted in the opening 23 the time 10 stamp is ready for use, and by contacting the face shown in Fig. V with an ink pad the Fig. V.

It will be noted that a slot 25 is provided 15 at the upper edge of the housing 1 to receive the stem of the watch A. As the winding and setting portion B extends beyond the housing 1, the watch may be readily wound and set.

20 I claim:

1. In a time stamp, a housing, a watch mounted in said housing, an elongated lever operatively connected to and extended radially from the shaft carrying the minute hand 25 of said watch, a rotary member operatively associated with said lever and provided with a slot through which said elongated lever extends, a series of members operatively associated with said slotted member for moving 30 two time-indicating pointers, one denoting the hour and the other the minute, and a printing pad having time-indicating characters thereon associated with said time-indicating pointers.

35 2. In a time stamp, a housing, a watch removably mounted in said housing, an elongated lever provided with an offset portion connected to and extended radially from the shaft carrying the minute hand of said watch,

40 a rotary cylindrical drum associated with said lever and having a slot formed through a wall thereof through which said elongated lever extends, a small gear wheel associated with said cylindrical drum, a large gear

45 wheel associated with said small gear wheel and adapted to be operated thereby, another small gear wheel associated with said large gear wheel and adapted to be rotated by and

in unison with said large gear wheel, a second large gear wheel operatively associated with said second-named small gear wheel, another cylindrical drum connected to said last-named large gear wheel and adapted to be operated thereby, said cylindrical drum carrying a time-indicating pointer, a smaller cylindrical drum mounted in said last-named cylindrical drum and carrying another time-indicating pointer, and a printing pad having time-indicating characters thereon co-operatively associated with said time-indicating pointers whereby the time indicated on the face of the watch is recorded on the bottom side of the time stamp.

3. A time stamp comprising, in combination, a casing having an opening formed in its rear face, a watch mechanism positioned within the casing with the minute hand shaft of the mechanism terminating within the confines of the casing and in alignment with the opening, resilient time indicating pointers located exteriorly of the casing, and means for connecting the minute hand shaft with the time indicating pointers, said means comprising a member rigidly mounted on the extremity of the minute hand shaft, a member interposed between said last named member and the time indicating pointers, and a lever carried by one of said members and adapted to engage slidably the other of said members.

4. A time stamp comprising, in combination, a housing, a watch mechanism mounted in the housing, and time indicating printing members located exteriorly of the housing and operated by the watch mechanism, the housing being provided with an opening for receiving the connections extending between the watch mechanism and the time indicating printing members, and these latter members being located laterally offset from the opening whereby jars imparted to the stamp during the use thereof will be inflicted upon the housing and not upon the connections.

In testimony that I claim the foregoing I hereunto affix my signature.

JOSEPH W. ADLON.
